UNITED STATES PATENT OFFICE.

ALBERT FRANÇOIS, OF DONCASTER, ENGLAND.

FILLING SPACES OR CAVITIES WHICH ARE DIFFICULT OF ACCESS WITH CONCRETE, CEMENT, OR THE LIKE.

1,391,678.

Specification of Letters Patent. Patented Sept. 27, 1921.

Application filed May 20, 1918. Serial No. 235,554.

To all whom it may concern:

Be it known that I, ALBERT FRANÇOIS, a subject of the King of Belgium, residing at Whitehouse Chambers, High street, Don-
5 caster, in the county of York, England, have invented certain new and useful Improvements in Filling Spaces or Cavities Which are Difficult of Access with Concrete, Cement, or the like, of which the following is
10 a specification.

This invention relates to the filling of spaces or cavities which are difficult of access (such for example as large fissures in the ground, crevices behind walls or pit tub-
15 bings which cannot be treated by hand methods) with concrete, cement or the like, the object being to accomplish this result in a rapid and economical manner.

Heretofore in mining or foundation work
20 where such cavities are met with and when the circumstances permit of its use it has been proposed to employ a filling material such as concrete which is allowed to siphon down naturally through pipes from the mix-
25 ing apparatus. When, however, siphoning cannot be carried on, a piston or ram pump is employed to generate the pressure necessary to force the filling material into the cavities but as concrete cannot be employed
30 in a ram pump a finely ground or liquid cement must be employed. The operation of filling by siphoning, while admitting of the use of a comparatively cheap filling material such as concrete is open to the objec-
35 tion that if ordinary concrete is employed the material while being fed through the system of pipes is liable to separate by gravity into different constituent layers, while, owing to the absence of pressure any
40 obstruction in the pipes causes the siphoning action to stop and the filling material to cease to flow. The resulting blockage allows the concrete to set in the piping and accordingly the filling process requires to be
45 suspended until the pipes have been dis-
mantled and cleaned. On the other hand the employment of a ram pump is open to the objection that it operates only slowly and also involves the use of large quantities of
50 pure cement which if used alone is a costly form of filling material.

According to the present invention the filling material is adapted to be fed rapidly and continuously through pipes into the
55 cavities to be dealt with by means of a low

pressure pump system, provision being made for bringing into operation higher pressures of supply immediately an indication is given that the low pressure pump system is inadequate and that a blockage is occurring or is
60 likely to occur in the pipes.

To this end the filling material is adapted to be fed into the cavities by means of a rotary or centrifugal pump and the piping is also connected up to a high pressure supply
65 system, involving, for example, the use of a ram pump, provision being made for indicating the pressure prevailing in the pipes during the filling operation in order that the high pressure system can be employed
70 when necessary. Instead of a ram pump being employed in the high pressure system, provision may be made for bringing into operation one or more supplementary centrifugal or rotary pumps, which may be
75 located in series with one another and with the low pressure pump system, immediately the pressure indicator shows that a stoppage is likely to occur under the lower pressures then prevailing. When centrifugal pumps
80 are employed it is preferred to use as the filling material a cheap form of concrete composed of cement powder and a finely ground and sieved material of approxi-
85 mately the same specific gravity as cement powder, such for example as furnace ashes or clinker, ground firebrick or the like, preferably in the proportions ranging up to four parts by weight of furnace ash or the like to one part by weight of cement powder.
90 If a series of centrifugal pumps are employed to generate the necessary pressure the aforesaid improved concrete mixture can be employed during the entire filling opera-
95 tion but if a ram pump is employed for higher pressures of supply, provision is made when bringing the ram pump into operation for cutting off the supply of concrete and substituting therefor a supply of liquid cement. If desired both the ram
100 pump and the centrifugal pump may be employed simultaneously, the ram pump in such cases being adapted when the centrifugal pump is operating to feed forward into the system of piping either a supply of fine cement or else a supply of water for the purpose of assisting the flow of concrete into the cavity which is being filled. Owing to the fact that the aforesaid improved concrete is composed of materials which have
105

approximately the same specific gravity there is no likelihood of the ingredients separating from one another under the influence of gravity while being fed through the system of pipes.

In order that the said invention may be clearly understood and readily carried into effect the same will now be described more fully with reference to the accompanying drawing, which shows diagrammatically and by way of example only, one embodiment of the invention, and in which:

A is a pit shaft and B is a cavity behind the pit tubing C which requires to be filled. 15 D is a main pipe extending down the pit shaft and communicating with the cavity B, its lower end being fitted with controlling valves E. At its upper end the main pipe D communicates with a branch pipe F fitted 20 with a centrifugal pump G and also with a branch pipe H fitted with a ram or piston pump I. Both the pipes F and H are provided with non-return valves J and J' respectively and communicate with a reservoir K fitted with a stirrer L into which the filling material is fed. Toward the upper 25 end of the main pipe D a pressure gage M is fitted for the purpose of indicating the pressure prevailing in the main pipe D. The pumps G and I are driven in any convenient manner from any suitable source of power.

In operation, the filling material which is preferably constituted by the aforesaid improved form of concrete is fed into the reservoir K. On the centrifugal pump being started the concrete is fed continuously and in large quantities at low pressure from the reservoir down the main pipe D into the cavity B. If desired the inlet end of the 30 ram pump may be placed in communication with a reservoir (not shown) containing water or cement so as to deliver slowly a supply of water or cement into the main pipe D simultaneously with the supply of concrete. The centrifugal pump G delivers the concrete at pressures up to about 60 lbs. per square inch, which is sufficient to overcome any ordinary obstruction which may arise in the piping and accordingly can be used until a large cavity such as B is practically filled. During the last stages of the filling operation, however, when the water with which the cavity is filled has to be forced out of the cavity into the surrounding soil, much higher pressures are necessary and at the proper moment (which is indicated to the operator by the pressure registered on the dial of the gage M) the low pressure pump G is stopped and the high 40 pressure pump I if not already operating is now brought into operation and the filling operation is completed. In the arrangement shown in the drawing and while the ram pump I is operating, pure cement (as 45 before stated) is fed into the reservoir K in

lieu of the concrete which was used when the pump G was operating.

Besides allowing of the major portion of the filling operation being effected with a cheap filling material, the use of a centrifugal or rotary pump has the advantage of more effectually mixing and thus improving the constitution of the cement while its use does not interfere with any natural tendency which may exist for the concrete to siphon 75 down through the piping.

What I claim and desire to secure by Letters Patent of the United States is:—

1. A method of consolidating and shutting off water from subterranean water bearing spaces which consists in establishing access to the space to be filled by means of small diameter boreholes, providing pipes and valves located in said boreholes which are capable of withstanding the pressures generated during the filling operation, connecting said pipes by means of a conduit to a system comprising a low pressure pump and a high pressure pump, providing means for cutting into or out of the system either of said pumps, forcing a filling material into said space by means of said low pressure pump, and subsequently forcing into said space under a higher pressure by means of said high pressure pump a filling material different from the kind first employed. 80

2. A method of consolidating and shutting off water from subterranean water bearing spaces which consists in establishing access to the space to be filled by means of small diameter boreholes, providing pipes and valves located in said boreholes which are capable of withstanding the pressures generated during the filling operation, connecting said pipes by means of a conduit to a system comprising a mixing apparatus, a low pressure pump and a high pressure pump, providing means for cutting into or out of the system either of said pumps, forcing a filling material into said space by means of said low pressure pump, and subsequently forcing into said space under a higher pressure by means of said high pressure pump a filling material different from the kind first employed. 90

3. A method of consolidating and shutting off water from subterranean water bearing spaces which consists in establishing access to the space to be filled by means of small diameter boreholes, providing pipes and valves located in said boreholes which are capable of withstanding the pressures generated during the filling operation, connecting said pipes by means of a conduit to a system comprising a mixing apparatus, a centrifugal pump and a ram pump, providing means for cutting into or out of the system either of said pumps, forcing a filling material into said space by means of said centrifugal pump, and subsequently 100

forcing into said space under a higher pressure by means of said ram pump a filling material different from the kind first employed.

- 5 4. A method of consolidating and shutting off water from subterranean water bearing spaces which consists in establishing access to the space to be filled by means of small diameter boreholes, providing pipes and valves located in said boreholes which are capable of withstanding the pressures generated during the filling operation, connecting said pipes by means of a conduit to a system comprising a mixing apparatus, a 10 low pressure centrifugal pump and a high pressure ram pump, providing means for cutting into or out of the system at will either of said pumps without interrupting the continuity of the flow of filling material, forcing through the pipe system by means of said centrifugal pump a mixture of cement and inert material of similar specific gravity so as to fill economically the main body of said space, and subsequently 15 forcing into said space, by means of said high pressure ram pump, pure cement grout immediately the centrifugal pump becomes inadequate to overcome the pressure in the pipe system, whereby the filling operation 20 is rendered continuous and the water bearing space made solid and dry thus enabling the excavation to be continued as though it were being carried through normally dry ground which would otherwise not be the 25 case owing to the capability of the water bearing space discharging water into the area under treatment.
5. Means for filling subterranean water bearing spaces, comprising a low pressure pump system adapted to force a filling material into said spaces, means for indicating the pressure prevailing in said pump system, and a high pressure pump system adapted 30 to force a different filling material into said spaces immediately an indication is given 35

that the low pressure pump system is inadequate, and that a blockage is occurring or is likely to occur.

6. Means for filling subterranean water bearing spaces, comprising a centrifugal pump for initially forcing a filling material into said spaces under pressure, and a ramp pump system for subsequently forcing filling material into said spaces under a greater pressure.

7. Apparatus for filling subterranean water bearing spaces or cavities comprising pipes extending into said space or cavity, a low pressure pump system for use in feeding concrete through said pipes into the cavity during the initial stages of the filling operation, a high pressure pump system for use in feeding cement into the space or cavity during the final stages of the filling operation, means for indicating the pressure prevailing in the pipe system throughout the filling operation, and means for bringing into operation said high pressure pump system immediately an indication is given that the low pressure pump system is inadequate 65 to deal with the prevailing pressure.

8. Apparatus for filling subterranean water bearing spaces or cavities comprising a conduit, a low pressure pump system connected with said conduit, and a high pressure pump system connected with the same 75 conduit, for the purpose described.

9. Apparatus for filling subterranean water bearing spaces or cavities comprising a conduit, a low pressure pump system connected with said conduit, and with a means for supplying a mixture of cement and aggregate to said conduit, means for indicating the pressure existing in said pump system, and a high pressure pump system connected with the conduit and with means for 80 supplying cement thereto, for the purpose 85 described.

ALBERT FRANÇOIS.
